[57] CLAIM

The ornamental design for an immunoassay test kit, as shown and described.

DESCRIPTION

FIG. 1 is a perspective view of an immunoassay test kit, showing our new design;

FIG. 2 is a right end elevational view thereof;

FIG. 3 is a left end elevational view thereof;

FIG. 4 is a top plan view thereof;

FIG. 5 is a side elevational view thereof, the opposite side elevational view being identical thereto;

FIG. 6 is a bottom plan view thereof; and

FIG. 7 is an exploded perspective view thereof, with parts removed.
